UNITED STATES PATENT OFFICE

ROMILLY T. RUTHERFORD, OF ALAMEDA, CALIFORNIA, ASSIGNOR TO WOOD-BARRETT CORPORATION, LTD., A CORPORATION OF CALIFORNIA

TIME SWITCH

Application filed December 9, 1929. Serial No. 412,799.

This invention relates to improvements in time switches of the kind adapted for use in automatically closing and opening circuits to a radio receiving set or other apparatus to be operated.

An object of my invention is to provide an improved coin or token controlled switch for automatically opening and closing circuits.

10 Another object of my invention is to provide an improved time switch which is so operated upon the insertion of a coin or token therein as to close a circuit to a radio receiving set or other apparatus, and maintain 15 the said circuit in a closed position for a definite period of time.

A further object of my invention is to provide an improved time switch which is adapted to receive coins of different denominations, and to maintain circuits in closed 20 positions for definite periods of time, dependent upon the particular kind of coin inserted therein.

A still further object of my invention is 25 to provide an improved time switch for closing and opening a circuit to a device to be operated, having coin slots of different sizes and means for maintaining a circuit in a closed position for a definite period of time, 30 dependent upon the size of the coin inserted therein.

Other objects more or less apparent will 35 present themselves or will be specifically pointed out in the description to follow:

35 In the accompanying drawings:

Figure 1 is a front elevation of a switch constructed in accordance with my invention;

Figure 2 is a sectional view taken on the line 2—2 of Figure 1;

40 Figure 3 is a sectional view taken on the line 3—3 of Figure 2; and

Figure 4 is a sectional view taken on the line 4—4 of Figure 1;

Referring to the drawings the numeral 1 45 designates a supporting member having chutes 2 and 3 mounted thereon in spaced relationship with one directly behind the other, each of which is suitable in size to accommodate a coin or token of a particular size or denomination.

Suitably secured at one end to the back of the supporting member 1, as by screws, is a thermostatic rod 4 comprised of two suitably attached strips of material, the inner strip being made from copper and the outer strip 55 from German silver. The thermostatic rod is bent outwardly or away from the supporting member when heat is applied to the two strips of material for the reason that the copper strip expands more rapidly than the 60 German silver strip. When the rod cools off the free end thereof moves inwardly or toward the supporting member due to the more rapid contraction of the inner or copper strip. An insulated wire 5, connected to 65 terminals 6 and 7 mounted on an insulated plate 8 which is supported on a bracket 9 secured to the front side of the supporting member 1, winds around the thermostatic rod 4 for a number of times, and serves as means 70 for applying heat to the said rod when a current of electricity is passed through the said wires.

Slidably extending through suitable slots located in a supporting bar 9 is a rod 10 having an upwardly and rearwardly bent part 11. The rod 10 extends through the supporting member 1 and is provided at a point at the rear of the latter with a slot or notch 12 within which the free end of the thermostatic rod 4 is located. When heat is applied to the rod 4 and its free end swings outwardly or away from the supporting member 1, the rod 10 is moved in the same direction. The rod 10 slidably extends through suitable 75 slots located at the lower parts of the chutes 2 and 3, and normally the said rod supports a coin or token dropped into either of the chutes. The rod 10 is provided at predetermined 80 points therein with notches 13 and 14, the former being adapted to register with the opening in the chute 2 and the latter being adapted to register with the opening in the chute 3. When the thermostatic rod 4 becomes heated and carries the rod 10 for a predetermined distance in a backward direction, the notch 13 is brought into registry 85 with the slot in the coin chute 2 thereby permitting a coin in the latter to drop therefrom. Likewise as the free end of the thermostatic 90

rod 4 is bent still farther away from the supporting member 1, the notch 14 is brought into registry with the slot in the coin chute 3, thereby allowing a coin or token therein to drop therefrom. The rearwardly bent part 11 of the rod 10 is adapted to slidably move in suitable notches 15 and 16 located respectively in the chutes 2 and 3 so as to intercept succeeding coins and prevent them from passing through the said chutes until the thermostatic rod 4 has cooled sufficiently to move back to its normal position.

Pivotaly mounted on a pin 17 secured to the bracket 9' and the supporting member 1 is a rod 18 carrying a cross piece 19 which is secured to one of its ends. The ends of the cross piece 19 extend into an arcuate slot 20 located in each of the chutes 2 and 3 and the said cross piece is adapted to intercept coins or tokens dropped into either of the said chutes. The rod 18 is normally maintained in an inclined position, with the cross piece positioned at the upper ends of the slots 20, by a spring 21 secured to an end of the said rod and to a projection 22 on the bracket 9'. A coin dropped into either of the chutes 2 or 3 will intercept the cross piece 19 and carry the same downwardly to a point adjacent the lower ends of the slots 20. Suitably secured to and mounted on the rod 18 at a point above the pivotal pin 17 is a mercury switch 23 comprising a glass container 23' having a suitable quantity of mercury therein. Extending into the glass container are two wires 24 and 25 the ends of which are positioned just above the bottom surface of the glass container. Also extending inside the glass container is a third wire 26 the inwardly disposed end of which is positioned at a point considerably above the bottom of the glass container. The mercury in the glass container is adapted to contact with the wire 26 only when the rod 18 and the glass container have been pivotally moved to a downwardly tilted position with the cross piece 19 located at the extreme lower ends of the slots 20 as shown by the dotted lines in Figure 1. The mercury will contact with the wires 24 and 25 when the cross piece 18 is positioned at a predetermined distance considerably above the extreme lower ends of the slots 20. The wire 24 is connected to a terminal 27, the wire 25 to a terminal 28, and the wire 26 to the terminal 7, each of the terminals being mounted on the insulated plate 8.

The terminal 6 is suitably connected to a device to be operated, such as a radio receiving set by a wire 29, and also to a source of electricity by a wire 30. The source of electricity is connected to the terminal 28 by a wire 31, while the device to be operated is connected to the terminal 27 by a wire 32.

In operation a coin or token of suitable size or denomination is inserted into either of the chutes 2 or 3, say chute 2, thereafter

intercepting and carrying the cross piece 19 to a point at the extreme lower ends of the slots 20. The rod 18 is thereby moved on its pivot to a downwardly tilted position, and the mercury in the mercury switch 23 moves to the opposite end of the glass container 23' where it contacts with all three of the wires 24, 25 and 26. The circuits to the source of electricity, to the device to be operated and to the wires 5 are all closed, thereby permitting a current of electricity to enter the switch and pass through the wires 5 to heat the thermostatic rod 4. The circuit to the device to be operated being closed, permits the said device to commence operating. As the current of electricity passes through the wires 5, the thermostatic rod 4 becomes heated and bends in such a manner as to move its free end outwardly away from the supporting member 1, thereby causing the rod 10 to gradually move to a point where the notch 13 therein registers with the opening through the chute 2. As soon as the notch registers with the opening through the chute 2, the coin or token therein is permitted to drop downwardly through the said chute and from the end thereof, thereby allowing the spring 21 to move the rod 18 on the pivot in such a manner that the cross piece 19 is carried upwardly in the slots 20. The rod 18 on its upward movement intercepts a projecting member 33 secured to the rearwardly bent part 11 of the rod 10, the said projecting member being so located as to permit the uninterrupted downward movement of the rod 18 when the thermostatic rod 4 is in its normal position. The projecting member 33, when the rod 10 moves rearwardly for a predetermined distance, is carried to a position where it is adapted to intercept the rod 18 and maintain the mercury switch 23 in such a position that only the wires 24 and 25 are in contact with the mercury. As soon as the mercury switch 23 is moved by the rod 18 to a position where the mercury therein no longer contacts with the wire 26, the flow of electricity through wires 5 ceases, and the thermostatic rod 4 is allowed to cool. As the thermostatic rod 4 cools and gradually resumes its normal position, the rod 10 as well as the projecting member 33 are moved forwardly, but only after the elapse of a certain interval of time and until the thermostatic rod 4 has moved the rod 10 sufficiently to carry the said member 33 free from the rod 18 are the circuits from the source of electricity and to the device being operated broken. During the time the projecting member 33 is in contact with the rod 18, the mercury switch 23 is maintained in a substantially horizontal position with the mercury therein contacting with only the wires 24 and 25. The circuit to the device being operated as well as the circuit from the source of electricity, are during this time maintained

in closed positions, thereby permitting the continued operation of the device. As soon as the thermostatic rod 4 has sufficiently moved the rod 10 and the projecting member 33 in 5 a forward direction to permit the rod 18 to resume its normal position, the mercury switch 23 is again moved to a position where the mercury therein does not contact with the wires 24 and 25. Upon the movement of 10 the mercury away from the wires 24 and 25, the circuits to the source of electricity and to the device being operated are broken thereby preventing the further operation of the device until another coin or token passes 15 through one of the chutes 2 or 3.

It will be noted that the normal position of the notches 13 and 14 in the rod 10 with reference to the respective chutes 2 and 3 are such that the rod 10 will have to be moved 20 by the thermostatic rod 4 for a greater distance in a backward direction to bring the notch 14 into registry with the opening through chute 3. Thus if a coin were inserted in chute 3 instead of in chute 2 as above described, the current would have to be applied to the thermostatic rod 4 for a longer 25 time in order to cause its free end to bend backward sufficiently to carry the rod 10 to a point where its notch 14 registers with the 30 opening through the chute 3. The added length of time required to both heat the thermostatic rod 4 and to cool the same, will proportionately maintain the circuits herein described in closed positions for a longer length 35 of time than if a coin were inserted in chute 2, thereby permitting the device to be operated for a greater length of time.

It is to be understood that any suitable type of switch may be satisfactorily employed with 40 my invention in place of the mercury switch herein described. It is also to be understood that my improved switch may be embodied in other forms included within the spirit of my invention as defined by the appended claims.

45 Having described my invention what I claim is:

1. A switch comprising a support having a coin or token chute thereon, a rod pivotally mounted on the support having means for 50 intercepting a coin or token dropped into the chute, the said rod being adapted to be moved by a coin or token when dropped into the chute, a thermostat mounted on the support, a plurality of contact points carried by the rod, the said contact points being connected with the terminals of a number of circuits, a wire leading from one of the terminals and one of the contact points to the thermostat, and means engaging with the thermostat for temporarily supporting a coin or token in the 55 chute.

2. A switch comprising a support having a coin or token chute thereon, means actuated by a coin or token dropped into the chute for 60 contacting with the terminals of a number of

circuits, a thermostatic rod mounted on the support having an electrical conductor connected to certain of the terminals, and means actuated by the thermostatic rod for temporarily supporting a coin or token in the 70 chute.

3. A switch comprising in combination with a support having a coin or token chute thereon, means pivotally mounted on the support and adapted to be actuated by a coin or token dropped into the chute, a plurality of circuits having terminals mounted on the support, contacting means carried by the first mentioned means for engaging with certain of the terminals, a thermostatic rod mounted 80 on the support having electricity conducting means connected to certain of the terminals and means actuated by the thermostatic rod for temporarily supporting a coin or token in the chute, the said last mentioned means being adapted to be actuated by the thermostatic rod to permit a coin or token to drop from the chute.

4. A switch comprising in combination with a support having a plurality of coin or token chutes thereon, each chute being adapted to receive a coin or token of certain size or denomination, a plurality of circuits having terminals mounted on the support, means extending into the chutes and adapted to intercept a coin or token dropped into either of the chutes, contacting means carried by the first mentioned means for engaging with certain of the terminals, whereby certain of the circuits may be closed at a certain time, and a thermostatic means associated with one of the circuits for controlling the movement of the coins or tokens through the 90 chutes.

5. A switch comprising in combination with a support having a plurality of coin or token chutes thereon, a plurality of circuits having terminals mounted on the support, means actuated by a coin or token dropped into either of the chutes having means for engaging with certain of the terminals, whereby certain of the circuits may be closed, and thermostatic means associated with one of the circuits for controlling the movement of a coin or token through either of the chutes.

6. In a time switch, a support having a plurality of coin or token chutes thereon, a plurality of terminals mounted on the support having a plurality of circuits connected thereto, a thermostatic rod mounted on the support having one of the circuits connected thereto, means actuated by a coin or token inserted into any one of the chutes, the said means carrying contacting means for engaging with certain of the terminals, whereby certain of the circuits may be closed, and means actuated by the thermostatic rod for controlling the movement of a coin or token through any of the chutes.

7. In a time switch, a support having a 130

plurality of coin or token chutes thereon, thermostatic means mounted on the support, having means associated therewith for controlling the movement of a coin or token passing through any of the chutes, an electricity conductor engaging with the thermostatic means, and means actuated by a coin or token dropped into any of the chutes for causing electricity to pass through the conductor.

8. In a time switch, a support having a plurality of coin or token chutes thereon, thermostatic means mounted on the support having means associated therewith for controlling the movement of coins or tokens inserted into the chutes, electricity conducting means for transferring heat to the thermostatic means having terminals mounted on the support, and means actuated by a coin or token passing through a chute, having contacting means adapted to engage with the terminals, whereby electricity may pass through the electricity conducting means to apply heat to the thermostatic means.

9. In a time switch, a support having a coin or token chute thereon, a thermostatic rod mounted on the support having means for controlling the movement of a coin or token through the chute, electricity conducting means mounted on the thermostatic rod having its terminals mounted on the support and connected to a source of electricity, and means actuated by a coin dropping through the chute having a mercury switch thereon, certain terminals in the mercury switch being connected to the terminals of the electricity conducting means.

10. In a time switch, a support having a coin or token chute thereon, thermostatic means for controlling the movement of a coin or token through the chute, means actuated by the thermostatic means for temporarily supporting a coin or token in the chute and means actuated by a coin or token passing through the chute for opening and closing an electrical circuit to the thermostatic means.

11. In a time switch, a support having a coin or token chute thereon, thermostatic means for controlling the movement of a coin or token through the chute, an electrical circuit leading to the thermostatic means, an electrical circuit leading to a device to be operated, and a pivoted rod extending into the chute and actuated by a coin or token passing through the chute for controlling the flow of electricity through the said circuits.

12. In a time switch, a support having a coin or token chute thereon, thermostatic means for controlling the movement of a coin or token through the chute, a plurality of electrical circuits having terminals mounted on the support, one of said circuits being connected to a source of electricity, another to a device to be operated and another to the thermostatic means, and means mounted on

the support and actuated by a coin passing through the chute for contacting with the terminals of the circuits, whereby the said circuits may be closed at certain times.

In testimony whereof I have affixed my signature.

ROMILLY T. RUTHERFORD.
